RUTH BRENNER, OF NEW YORK, N. Y.

STAGE DECORATING

Application filed September 27, 1930. Serial No. 484,731.

My invention relates to stage wings and drop curtains and more particularly to wings and drop curtains to be used for musicals and other theatrical productions.

5 Musical and nearly all other shows, such as dramatic productions, use a proscenium, arch-built or draped, as a frame for the scenes to be shown. This arch is apart from any of the architectural construction of the theatre building, and it travels with the 10 scenery, should more than one theatre house the show. As a rule, these arches are composed of one velvet covered "flat" shoved in from each side and with a matching border 15 hung from the flys. All three parts may be moved closer together or further apart, to regulate the opening for the stage. As the two wing pieces are each only six feet wide, the opening cannot be closed. Most stages 20 close them in to an opening of from twenty to forty feet with an average of thirty feet for dramatic productions and intimate revues.

Another type of arch is constructed of 25 wooden frames or of one frame in the shape of an arch with draw curtains directly behind it to close off the inner stage. This is the type most generally used for musical shows, and sometimes there is a second arch 30 with its own set of draw curtains some feet further back. Its purpose is to obtain a considerable smaller scene space for intimate numbers. The main arch is always placed behind the house or act curtain and is far 35 enough away from this to leave space for act in "one". All these arches are held in place with regular stage braces.

In all of these arrangements, the control 40 of various settings is obtained by the wings positioned to various positions between the front and back of the stage and accordingly, only very limited stage effects can be produced.

It is one of the prime objects of my invention to provide an arrangement of scenery 45 which may be utilized to obtain as small or as large scene space as is desired for various stage plays, musicals, intimate revues, or for any acts which are shown on the legitimate stage.

A further object of my invention is to provide a novel arrangement of proscenium which controls all stage effects from the front of the stage.

Heretofore wings, set pieces, and properties, generally used on the stage, have been supported on elongated arms as is commonly done with easels. In such an arrangement, only one movement, such as tilting the member back and forth, was possible. Furthermore, the supporting arm extends to the rear of the piece. Inasmuch as the actors, in moving to and from the stage, must pass between the wings, pieces and other properties, the arms formed serious obstructions, which impeded ready ingress and egress from the stage.

A further object of my invention is to provide a novel support for stage pieces which will enable movement thereof in any desired 70 direction and which will so be placed as to leave the space between stage pieces unobstructed.

With these and other objects in view, my invention consists in the arrangement, combination, and construction of the various parts of my improved device as described in the specification, claimed in my claims, and shown in the accompanying drawings in which:

Figure 1 is an elevation front view of my improved device showing six wings, three on each side and three drop curtains.

Figures 2 and 3 are elevation front views of my improved device showing various arrangements and designs which may be effected.

Figure 4 is an elevation back view of one wing showing the ball and socket, the slide groove, the ratchet, and method of support.

Figures 5 and 6 are parts showing the ratchet and slide groove.

Figure 7 is a diagrammatic view showing the stage arrangement.

In Figure 1, I have shown nine sections. 95 However, it will be obvious, to those skilled in the art, that a greater or smaller number of sections may be used. All nine pieces are wooden frames covered with any material desired. All are mounted close to each other,

and in the front of the stage. The three hanging borders #1, #2, #3 are framed like the wings and they are hung so close together that they appear fastened together, except 5 when they are observed in the process of change.

Likewise, the wing pieces 4, 5, 6 and the wing pieces 7, 8, 9 stand directly behind each other in such a way, that the six pieces extended could form a large door. 10

Figure 3 is an illustration showing the wing pieces 4, 5, 6, 7, 8, and 9 closed in to form a large door. These are to be finished off at the top by the border pieces 1, 2, 3 in such a 15 way that the third piece reaches the floor and completely closes off the stage proper. In this case, the wing pieces would remain at the sides, or they could close after the border pieces have dropped or at the same time as they are dropping, giving the effect of a 20 double closing-off of the stage. Or, the side pieces need not complete their closing, but may compose themselves into any "regular" composition required by the art director. 25 By "regular" is meant that the edges of the borders are on a true horizontal plane and that the edges of the wings are on a true vertical plane.

Figure 2 illustrates how, besides performing on regular horizontal and vertical lines, 30 all nine pieces would be capable of tilting vertically, sliding in a horizontal arc as well as sliding in and out. This would achieve an unlimited number of modernistic designs. 35 These effects would be created in the borders by making them hang crooked, according to marked ropes handled from the fly gallery.

The manner of operating the wing is illustrated in Figure 4, which is a rear view of 40 one wing, each wing being operated as the one illustrated. The wing is composed of a wooden frame and a cross piece 2. On cross piece 2 is supported a ball and socket 3 which allows the wing to move in any direction. 45 As will be understood, the wing when once positioned is held rigidly in position. The socket 3, in conjunction with the socket 4, will permit the wing to be tilted and moved in any direction.

For sliding in and out, I have provided two 50 arms 5, each having a groove 6 with pins 7 which hold the two pieces rigid, one end of one arm 5 being connected directly to the ball of the ball and socket, and one end of 55 the second piece being connected to one side of the pivot 4. The other side of the pivot 4 is connected to brace 8 which is held by flange 10 and bolted to the floor with bolts 11. The entire arrangement is so placed that the 60 wings can be slid completely out, or all the way back.

Figure 5 illustrates the details of the pivot 4, showing the teeth 12. Member 8 is rigid, member 5 is moved up or down as desired, 65 and the teeth 12 are moved to engage each

other and are held in position by the bolt and nut 13.

Figure 6 illustrates arms 5 showing the pins 7 which support the arms. The arms, as shown, may be slid to any desired position 70 and then fastened by bolt and nut 9.

With this equipment, any shaped opening, required for the mood of the scene to be played behind it, may be obtained. These 75 openings, whether regular or irregular in shape, may be closed-in or enlarged to any proportion. Settings may be used behind this arch, but its chief value, aside from the artistic effect or novelty, is to eliminate wing settling entirely so as to make possible instantaneous changes, and minimize the stage 80 crew and labor when troupeling the show.

It is obvious, that with the use of this arch—used with draperies with or without 85 props or set pieces, and with possibly some painted drops, the original cost for a production would be a fraction of the customary expense.

Although I have illustrated my invention 90 with a specific arrangement of the wings and drops, other arrangements, such as an interlacing of the wings and drops, may be followed. Furthermore, although for purposes 95 of illustration the wings and drops are shown near the front of the stage, they may also be arranged at any point along the stage and come within the scope of my invention.

Although for purposes of illustration, I 100 have shown my invention in connection with stage wings, it will be obvious that it has more general application as to other stage pieces, properties, etc.

Thus, the new brace or support, herein 105 shown, may be used for all pieces which must have some extraneous support. By means of these supports, any piece could be readily and quickly placed on the stage in any angle and could as quickly be removed. The pieces could be lifted above the floor, thus conserving floor space. Inasmuch as 110 the braces extend in the plane of the pieces, they leave the passages to the stage clear, eliminating the necessity of stepping over the stage braces, as heretofore.

It will also be evident that the braces may 115 be readily detachable from the pieces.

What I claim is:

1. In combination, a stage, a plurality of 120 wings arranged at the front of the stage and adjacent each other, and means for raising and lowering said wings, and means for moving said wings in and out and a universal member for rocking said wings about any axis whereby said wings can be arranged in any position relative to each other.

2. In combination, a stage, a plurality of 125 wings at the front of the stage and at both sides and top, and means for raising and lowering said wings, means for moving said wings in and out and a universal member 130

for tilting said wings at any angle whereby said wings can be arranged in any angular position relative to each other to produce any shape and size of stage opening.

3. In combination, a stage, a plurality of wings at the front of the stage, means for mounting said wings, and means for moving said wings into any desired angle whereby said wings vary the size and shape of the stage opening.

4. In combination, a stage wing, a portable support therefor, means secured to said support and wing for rocking said wing to any desired angular position about said support, said support being secured to the rear of said wing whereby it is at all times invisible.

5. In combination, a stage wing, a portable support therefore, a ball and socket means mounted on said support and carrying said wing whereby the wing can be rocked to any desired angular position about said support said support being secured to the rear of said wing whereby it is at all times invisible.

6. In combination, a stage wing, a portable support therefore, means secured to said support for rocking said wing to any desired angular position about said support, and means for moving said wing along said support and for rocking it about a horizontal axis; and means for raising and lowering said wing whereby said wing may assume any position in a fixed space and any angle in the assumed position.

7. In combination, a stage wing, a support therefore, a ball and socket connecting said wing to said support means for rocking said wing to any desired angular position about said support, and means for moving said wing along said support.

8. In combination, stage pieces, portable floor mounted braces for supporting said pieces extending in a direction parallel to the plane of the pieces and in the rear thereof, and means on said braces permitting the setting of said pieces in any desired angle and position.

9. In combination; a stage wing; a bracket member having telescoping parts; a ball and socket member secured to the bracket member and to said wing whereby said wing is movable to any desired angle about said bracket member; said telescoping parts permitting said wing to be moved in and out to any desired position; and a pivotal support for said telescoping member to permit said wing to be raised and lowered to any desired angular position.

10. In combination; a stage wing; a bracket member having telescoping parts; a ball and socket member secured to the bracket member and to said stage wing whereby said wing is movable to any desired angle about said bracket member; said telescoping parts permitting said stage wing to be moved in and out to any desired position; and a pivotal

support for said telescoping member to permit said stage wing to be raised and lowered to any desired angular position, said bracket member being secured to the rear of said stage wing whereby it is invisible.

11. In combination; a wing; a bracket member having telescoping parts; a ball and socket member secured to the bracket member and to said wing whereby said wing is movable in any desired angle about said bracket member; said telescoping parts permitting said wing to be moved in and out to any desired position; and a pivotal support for said telescoping member to permit said wing to be raised and lowered to any desired angular position, and further wings having similar support for moving said wing to any angular position, said wings being located near the front of the stage and at both sides and top whereby any desired opening effect can be obtained.

12. In combination; a wing; a bracket member having telescoping parts; a ball and socket member secured to the bracket member and to said wing whereby said wing is movable in any desired angle about said bracket piece; said telescoping parts permitting said wing to be moved in and out of any desired position; and a pivotal support for said telescoping parts to permit said wing to be raised and lowered to any desired angular position; and further wings having similar supports for permitting said wings to be moved to any angular position, said wings being located near the front of the stage and at both sides and top whereby any desired opening effect can be obtained, said bracket members for supporting said wings extending in the direction parallel to the plane of the wing whereby the space between the wing is left unobstructed.

In testimony whereof I affix my signature.
RUTH BRENNER.
